UNITED STATES PATENT OFFICE.

JOHN M. PATTERSON, OF ROCHESTER, NEW YORK.

DESIGN FOR AN AUTOMOBILE LICENSE-PLATE.

59,374.

Specification for Design.

Patented Oct. 11, 1921.

Application filed May 13, 1921. Serial No. 469,380. Term of patent 14 years.

To all whom it may concern:

Be it known that I, JOHN M. PATTERSON, a citizen of the United States, residing at Rochester, in the county of Monroe and State of New York, have invented a new, original, and ornamental Design for Automobile License-Plates, of which the following is a specification, reference being had to the accompanying drawing, forming part thereof.

The figure is a perspective view of an automobile license plate of my new design.

I claim—

The ornamental design for an automobile license plate as shown.

In testimony whereof I affix my signature.

JOHN M. PATTERSON.
